LOCK DEVICE FOR DIAL TELEPHONES

Application filed July 1, 1927, Serial No. 202,821. Renewed February 10, 1930.

This invention relates to what are known as dial telephones employing rotary, reciprocating dials, whereby the operator or user of the telephone may directly call the desired phone number and exchange, and particularly to the provision of means for controlling the manually operated dial to prevent the use thereof by others than authorized parties or individuals; and the object of the invention is to provide a lock or control device in the form of a casing adapted to be mounted upon the dial of the telephone and locked in engagement therewith in such manner as to prevent the use of the telephone; a further object being to provide a lock device which is so constructed as to prevent the detachment of the device from the dial controlled by the same, and further which will prevent the rotation of the call dial by a tool or implement inserted into the control and lock device; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of our improvement are designated by suitable reference characters in each of the views, and in which:—

Fig. 1 is a plan view diagrammatically illustrating the base of a telephone of the dial type, showing our improved lock device mounted thereon.

Fig. 2 is a section on the line 2—2 of Fig. 1.

Fig. 3 is a bottom plan view of the device shown in Figs. 1 and 2.

Fig. 4 is a plan view of a modified form of lock which we employ; and,

Fig. 5 is a bottom plan view of the lock shown in Fig. 4.

In Fig. 1 of the drawing, we have indicated at 10 in dot and dash lines, the base of a telephone of the call or dial type, and at 11, the dial portion of said case having at one point the hook-shaped stop arm 12, and the circumferentially spaced apertures 13 in the rotating dial 14, which is indicated

in dot and dash lines in Fig. 2 of the drawing. At 15, we have shown one of our improved lock or control devices, which in the construction shown, is in the form of a sheet metal cup-shaped body.

The cup-shaped body 15 consists of a top wall 16 and a downwardly extending flange 17, joined with the top 16 through a beaded rim 18. The flange 17 is provided at a predetermined point with an aperture 19, in which the stop arm 12 is located when the device is mounted upon the dial 11, it being understood that the arm 12 is stationary, and this arm serves to lock our improved device 15 against rotation on the dial in combination with the other locking means, later described.

Rotatably mounted in a bearing 20 centrally of the top face of the device, is a lock disk 21 mounted on the inner face of the top 16, and the peripheral portion of the lock disk 21 is provided at spaced intervals with hook-shaped fingers 22, three of which are employed in the construction shown. These fingers are adapted to enter and pass through a corresponding number of apertures 13 in the rotatable dial 14, and by rotating the lock disk 21, the vertical shafts 22a of the fingers 22 are adapted to be brought into position adjacent the right hand walls of the apertures 13 as clearly seen in section in Fig. 1 of the drawing, in order to prevent rotation of the dial 14 from right to left or clockwise when our improved device is mounted thereon and in locked position, it being understood that said device itself is locked against movement and displacement between the stop arm 12 and the respective fingers 22, it being further understood that when the dial 14 is in normal position, it has no movement anti-clockwise or from left to right.

The lock disk 21 is retained in its operative and inoperative positions, by providing at a predetermined point in the periphery thereof, and intermediate two of the fingers 22, a radially extending tongue 23 formed by two radial slots 24. The outer corner portions of said tongue are turned inwardly or downwardly to a slight extent as seen at 25,

in order to permit of the frictional passage of said tongue over a stop lug 26 in the rotation of the disk 21. The lug 26 is pressed downwardly from the material of the top 16 in the construction shown, or may be formed in any desired manner and is adapted to engage the side walls of the tongue 23 to retain the disk 21 in its several positions. The disk 21, in the construction shown, is fixed to the bearing 20, and a suitable key 27, having an angular or other shank portion 28 corresponding with a similar contour in the bore of the bearing 20 permits of the rotation or operation of the lock disk 21 in moving the same into operative and inoperative positions in attaching and detaching our improved lock or control device.

In the use of our improved device, and in the operation of placing the same upon the dial, the figures 22 are in a position to the left of that shown in Fig. 3 of the drawing, or in other words, the lock disk 21 has been rotated anticlockwise as seen in Fig. 3 to bring the lug 26 into engagement with the other slot 24. In this position, the fingers 22 will pass freely through three of the holes 13 in the dial 14, and the lock arm 12 will pass into the aperture 19 in the flange 17 of the device 15. When in this position, the key 27 is inserted into the bearing 20, and the lock disk 21 is rotated to bring the same into the position shown in Fig. 3 of the drawing, and also represented in Fig. 1 of the drawing, in which position, the shanks 22a of the fingers 22 are adjacent the walls of the apertures 13. The device is now locked in position, and cannot be removed from the dial until the key 27 has been re-inserted, and the bearing rotated in the opposite direction or into the first named position, after which the device 15 may be withdrawn from the dial, and the telephone is again put in operation. It will be understood that any particular type of control may be employed for engaging and operating the lock disk 21 or for moving the fingers 22 into operative and inoperative positions.

In Figs. 4 and 5 of the drawing, we have shown a modification wherein the disk 21 is pivoted to the top member 16 of the device 15 by means of a rivet bearing 29. Instead of rotating the disk 21 centrally as in Figs. 1 to 3 inclusive, we provide a key actuated latch member 30 which is arranged and mounted in the top wall 16 of the device, adjacent the peripheral edge of the dial 21, and the radially extending arm 31 of the latch device 30 is adapted to engage oppositely disposed shoulder portions 32 and 33, formed by recessing the peripheral edge of the disk 21 as seen at 34.

As in Fig. 3 of the drawing, the disk as shown in Fig. 5, is illustrated in its operative or locked position. By inserting a key into

the aperture 35 of the latch device 30 to rotate the arm 31 clockwise as seen in Fig. 5 of the drawing, the disk 21 will be moved anticlockwise by engagement with the shoulder 32. In moving the disk 21 from inoperative position to the position shown in Fig. 5, the arm 31 engages the shoulder 33.

Except for the modifications above described, the device 15 shown in Figs. 4 and 5 of the drawing, is identical in construction with the device shown in Fig. 3 of the drawing. In other words, the disk 21 is provided with three fingers 22 and with the tongue 23 engaging the lug 26. It will also be understood that other means may be provided for moving and controlling the movement of the fingers 22 or other locking means which may be employed for securing the device 15 in connection with and against displacement from the dial, for the purpose of preventing the use of the telephone by others than authorized parties.

It will also be apparent that with our improved control for the call dial of telephones of the class under consideration, while the lock and control device prevents the use of the telephone in making a call, it does not, in any way, interfere with the reception of a call. The device is intended primarily for use in preventing the excessive use of a telephone in offices, apartments or like places, where it is known that unauthorized parties or individuals make use of a telephone, without privilege or authority from the subscriber.

It will be understood that our invention is not limited to the details of construction herein shown and described, and various changes therein and modifications thereof, may be made within the scope of the appended claims, without departing from the spirit of our invention or sacrificing its advantages.

Having fully described our invention, what we claim as new and desire to secure by Letters Patent, is:—

1. The combination with the call dial of a telephone, of a lock device mounted and supported in connection with and adapted to control the use of the operative element of said dial, means for preventing the displacement of said device from said dial, said device comprising a cup-shaped body mounted directly upon and encircling said dial.

2. A lock device for the call dials of telephones comprising a cup-shaped body adapted to be mounted upon and encircling said dial, manually controlled means for securing said device against displacement from the dial and for retaining said dial in inoperative position, a key for controlling the operation of said last named means, said manually controlled means comprising a rotatable disk, and a plurality of hook-shaped fingers carried by and movable with said disk.

3. A lock device for the call dials of tele-

phones comprising a cup-shaped body adapted to be mounted upon and encircling said dial, manually controlled means for securing said device against displacement from the dial and for retaining said dial in inoperative position, a key for controlling the operation of said last named means, said manually controlled means comprising a rotatable disk, and a plurality of hook-shaped fingers carried by and movable with said disk, and means for retaining said disk in operative and inoperative positions.

4. The combination with the call dial of a telephone employing a rotary, reciprocating member, and a stop arm cooperating with said member, of a lock device engaging said arm and said reciprocating member and adapted to retain said member against movement, said device comprising a cup-shaped casing mounted upon and encircling said member, said casing having a recess to receive said arm, to key the casing against rotation on said dial.

5. The combination with the call dial of a telephone employing a rotary, reciprocating member, and a stop arm cooperating with said member, of a lock device engaging said arm and said reciprocating member and adapted to retain said member against movement, said device comprising a cup-shaped casing mounted upon and encircling said member, said casing having a recess to receive said arm to key the casing against rotation on said dial, and the locking means of said device comprising a hook-shaped finger adapted to pass through and cooperate with the reciprocating member of said dial.

6. The combination with the call dial of a telephone employing a rotary, reciprocating member, and a stop arm cooperating with said member, of a lock device engaging said arm and said reciprocating member and adapted to retain said member against movement, said device comprising a cup-shaped casing mounted upon and encircling said member, said casing having a recess to receive said arm to key the casing against rotation on said dial, the locking means of said device comprising a hook-shaped finger adapted to pass through and cooperate with the reciprocating member of said dial, and means for moving said hook-shaped finger into operative and inoperative position.

7. The combination with the call dial of a telephone employing a rotary, reciprocating member, and a stop arm cooperating with said member, of a lock device engaging said arm and said reciprocating member and adapted to retain said member against movement, said device comprising a cup-shaped casing mounted upon and encircling said member, said casing having a recess to receive said arm to key the casing against rotation on said dial, the locking means of said device comprising a hook-shaped finger adapted to

pass through and cooperate with the reciprocating member of said dial, and means for moving said hook-shaped finger into operative and inoperative position, said means involving a key.

8. A device of the class described comprising a cup-shaped casing, the peripheral wall of which is provided with a recess, a disk rotatably mounted on the inner face of the top of said casing, a plurality of fingers carried by said disk, and means involving a key for moving said disk clockwise and anti-clockwise into operative and inoperative positions, and means for retaining said disk in such positions.

9. A device of the class described comprising a cup-shaped casing, the peripheral wall of which is provided with a recess, a disk rotatably mounted on the inner face of the top of said casing, a plurality of fingers carried by said disk and means involving a key for moving said disk clockwise and anti-clockwise into operative and inoperative positions, and means for retaining said disk in such positions, said last named means comprising a spring tongue adapted to engage a lug on said casing.

10. The combination with the call dial of a telephone, of a lock device comprising an inverted cup-shaped body mounted directly upon and encircling said dial, said device consisting of a top wall arranged over and concealing said dial, and a depending annular wall encircling the periphery of said dial, and said device when mounted upon the dial preventing the operation thereof.

11. The combination with the call dial of a telephone, of a lock device comprising an inverted cup-shaped body mounted directly upon and encircling said dial, said device consisting of a top wall arranged over, and concealing said dial, a depending annular wall encircling the periphery of said dial and said device when mounted upon the dial preventing the operation thereof, and means engaging part of the dial for preventing the displacement of said device therefrom.

12. The combination with the call dial of a telephone, of a lock device comprising an inverted cup-shaped body mounted directly upon and encircling said dial, said device consisting of a top wall arranged over and concealing said dial, a depending annular wall encircling the periphery of said dial and said device when mounted upon the dial preventing the operation thereof, means engaging part of the dial for preventing the displacement of said device therefrom, and means for moving said first named means into operative and inoperative position.

13. The combination with the call dial of a telephone, of a lock device comprising an inverted cup-shaped body mounted directly upon and encircling said dial, said device consisting of a top wall arranged over and

encircling said dial, a depending annular wall encircling the periphery of said dial, and said device when mounted upon the dial preventing the operation thereof, and key-actuated means for engaging part of the dial to prevent the displacement of said device therefrom.

14. The combination with the call dial of a telephone employing a rotary, reciprocating member and a stop cooperating with said member, of a lock device comprising an inverted cup-shaped casing adapted to be placed over and enclose said member, and engaging said arm and member to prevent the use thereof.

15. The combination with the call dial of a telephone, of a lock device involving a casing adapted to be mounted upon and entirely enclose said dial, and said casing including means constituting a part thereof for engaging the operative elements of the dial to prevent the use thereof and to retain the casing against displacement from the dial.

In testimony that we claim the foregoing
as our invention we have signed our names
this 27th day of June, 1927.
